UNITED STATES PATENT OFFICE.

DIRK A. KLEIMAN, OF OGDEN, UTAH.

CHANGEABLE EXHIBITOR FOR CARS.

Application filed March 18, 1922. Serial No. 544,879.

To all whom it may concern:

Be it known that I, DIRK A. KLEIMAN, a subject of the Queen of Holland, residing at Ogden, in the county of Weber and State 5 of Utah, have invented certain new and useful Improvements in a Changeable Exhibitor for Cars; and I do hereby declare the following to be a full, clear, and exact description of the invention, such as will 10 enable others skilled in the art to which it appertains to make and use the same.

This invention relates to a changeable exhibitor for railway cars, particularly of the urban and inter-urban type.

15 One object is to provide an apparatus of this kind which is controlled by a novel means from an obstacle on a trolley wire, the trackway or otherwise disposed in the path of travel.

20 Another object is to provide such an apparatus having a novel escapement means operable by mechanism cooperating with obstacles in the path of travel.

Another object is to provide a spring- 25 actuated exhibitor having a motor operable to wind the spring, and a switch in the motor circuit controlled by operation of the apparatus.

It is further aimed to provide a novel 30 means for paying out and rewinding a flexible exhibitor member or tape.

The invention aims to provide an exhibitor 35 of the general construction and having the features and details hereinafter described with reference to accompanying drawings 40 illustrating one practical embodiment. Additional objects and advantages will become apparent from a consideration of said description and drawings.

In said drawings:—

Figure 1 is a fragmentary longitudinal 45 sectional view through a trolley car equipped with my exhibitor and shown in connection with operating mechanism associated with the trolley wire;

Figure 2 is a plan view of the trolley wire, obstacle thereat and associated operating mechanism;

Figure 3 is an enlarged detail of the parts 50 of Figure 2 looking from the right of Figure 1;

Figure 4 is an enlarged front elevation of the exhibitor alone;

Figure 5 is an enlarged vertical section

through said exhibitor on line 5—5 of Figure 4;

Figure 6 is a horizontal sectional view on the line 6—6 of Figure 4;

Figure 7 is a horizontal sectional view on the line 7—7 of Figure 5;

Figure 8 is a fragmentary plan view of the exhibitor to exemplify the switch for the main spring;

Figure 9 is a vertical sectional view illustrating the exhibitor tape winding spring mechanism;

Figure 10 is a detail fragmentary plan of the exhibitor tape;

Figures 11 and 12 are detail views exemplifying the action of the escapement 70 device and associated cam; and

Figure 13 is a diagram of the electrical apparatus used.

Figure 14 is a detail sectional view illustrating the detachable mounting of one of 75 the exhibitor tape spools or drum;

Figure 15 is a fragmentary view in rear elevation of a modified form of escapement operating means, and

Figure 16 is a side elevation of said means 80 of Figure 15.

Like reference characters designate like or similar parts throughout the views of the drawings.

The improvements are shown as associated 85 with a street car at A. As the invention is capable of application to cars generally, such illustration is to be taken as conventional. The trolley or overhead feed wire of the car A is shown at B as engaged by the 90 wheel C carried by trolley pole D. One of the usual transverse supporting wires for the wire B is shown at E.

An exhibitor per se is illustrated and may be mounted at any suitable location 95 within the car A as at the front or rear thereof in a position for view by all passengers. The exhibitor may have a casing in superposed sections 10 and 11 and within the section 10 a plurality of spools or drums 100 12 are journaled to turn on vertical axes. Said spools 12 are preferably removably secured in place in any suitable manner. To this end and as shown in Figure 14, plates 13 may be fastened to the bottom wall of 105 section 10 and of such size as to form end flanges or disks for the drums 12, equivalent to the end flanges or disks 14 thereof.

The cores of drums 12 are provided with a stud at 15 to removably enter and turn in a socket 16 of plates 13. Operating gear wheels at 17 are located within the frame 10 and have stub shafts 18 to mount the same which are journaled in a supporting wall 19 of said sections. Coupling disks or plates 20 are provided on the stub shaft 18 below support 19 and provided therein are conical sockets 21 to be engaged by a latch 22, having a correspondingly shaped conical socket, and which latches are slidably mounted in recesses 23 of the cores of the spools 12 and urged outwardly by expansive coil springs 24 disposed therein. Slight movement of the spools 12 intermediate the plates 13 and 20 is permissible to permit attachment and detachment of the stud 15 with the socket 16. Any suitable means may be provided to couple the spools 12 to the plates 20 for unitary movement and to this end, a pin 25 may extend from each plate 20 and enter radial slots 26 in the flanges 14. It will thus be realized that the drums 12 may be readily attached and detached from the plates 20 and 13.

An elongated tape or ribbon 27 is provided which may be divided into panels 28 containing exhibition matter, for instance at the top thereof a name of the street or avenue or other location forming the next stop and below which suitable advertising matter may, if desired be delineated. This tape has one end secured removably or otherwise to each of said spools 12. To the left, at the front, a panel may be provided at 29 and have delineated thereon "Next stop" to form a key cooperating with the stop indication at the top of the panels 28. In actual use, the tape 27 will contain panels 28 for each block along its route so that the device will serve sufficiently as a street indicator as well as an effective advertisement.

Attention is called to the fact that the advertisement cooperates with the street indication, inasmuch as it relates to a business or profession adjacent the particular stop indicated on the panel 16. The tape 27 is adapted to travel across and for exposure at an exhibiting opening 30 in the section 10. In order to properly guide the tape 27, suitable idler rollers may be provided within section 10 as at 31. In order to connect the spools 12 and tape for removal from the casing, the front wall and end walls thereof may be removable or hinged as is obvious.

The tape is adapted to be driven positively and by any suitable means. To this end, a spring motor may be employed utilizing the shaft 33 to which one end of a clock spring 34 is fastened and which spring is located within a suitable casing 35 and which has its other end secured thereto as

at 36. Casing 35 has a sleeve 37 in which the shaft 33 is journaled and which sleeve in turn is journaled in the support 19. Formed integrally with or otherwise on the sleeve 37 is a bevel gear wheel 38.

In mesh with the gear wheels 17, are bevel gear wheels 39 keyed to suitable shafts 40, journaled in bearings 41 rising from the supporting wall 19. The inner portions of the shafts 40 are reduced as at 41^a and keyed or splined thereto and slideable on the portions 41^a are bevel gear wheels 42. The gear wheels 42 are adapted to mesh one at a time and selectively with the gear wheel 38. Any suitable means may be provided to accomplish the shifting of the gear 42. For instance a yoke is provided at 43 having forks 44 engaging the gears 42 in such manner as not to interfere with rotation thereof. Yoke 43 is part of a lever 45 which may be journaled to swing horizontally as from a shaft 46 and which may have a manipulating handle at 47. The construction described forms a means whereby the motor 34 may wind the tape 27 for forward or reverse movement towards the opening 30. The casing 10 may have an opening at 48 to permit insertion of the hand of the operator to grasp the handle 47.

A main shaft 49 is journaled in the upper and lower walls of the section 11 and extends into the casing 10. Shaft 49 is adapted to be driven in the same direction as the shaft 33 and is in alignment with the latter. Shaft 33 practically forms an extension of said shaft 49. Secured to the shaft 49 is one end of a clock spring 50 whose other end as at 51 is secured to the section 11. Journaled on the shaft 49 is a worm wheel 52 in mesh with which is a worm 53 on a shaft 54 adapted to be driven from a motor 55, preferably of the electric type, in order to simultaneously drive the shafts 49 and 33 and thus simultaneously rewind spring motors 34 and 50. Worm wheel 52 has an inner gear rack 56 with which a pinion or gear wheel 57 meshes and which also meshes with the gear wheel 58 keyed to the shaft 49. Loose on the shaft 49 below gear wheels 57 and 58 is a large gear wheel 59 to which a stud or shaft 60 is rigidly fastened and on which gear wheel 57 is journaled. Below gear wheel 59, a ratchet wheel 61 is fast on shaft 49 and cooperating therewith is a spring pressed pawl 62 journaled on the stud 60. When the spring 50 unwinds, its motion is transmitted through the gear wheel 58 from shaft 49 to gear wheel 57 and thence to gear wheel 59. When the spring is wound, shaft 49 is turned through the turning of the worm 53, worm wheel 52, gear wheel 57 and gear wheel 58, the pawl 62 permitting a slip connection of the wheel 59 relatively to shaft 49.

Shafts 33 and 49 are not positively con-

- nected as a single shaft since at times they are required to move independently. To this end, the shaft 49 may have an extension 62^a journaled in a socket 63 in the shaft 33. To this end, a pawl 64 is pivoted at 65 to the shaft 49. This pawl cooperates with teeth of a ratchet at 66. The ratchet 66 is positively moved by the pawl 64 when shaft 49 is turned to wind the spring.
- 10 When shaft 49 turns in an unwinding direction, it moves independently of and relatively to shaft 33 during which action the pawl 64 freely slips over the teeth of ratchet 66. In order to prevent reverse rotation of the shaft 33, a pivoted pawl 67 is provided within the casing 10 and engages other ratchet teeth of the ratchet 66 as at 68.
- Through expended motion from spring 50, shaft 49, through the medium of gear 20 wheel 59 and a gear wheel 69 keyed on the shaft 46 within the section 11, shaft 46 is turned. Keyed on shaft 46 is a gear wheel at 70. Journaled on a vertical axis within the section 10 is a shaft 71 which may carry 25 one or more feed rollers 72 provided with projections 73 adapted to enter projections 74 provided along the edges of the tape 27. Shaft 71 is adapted to be driven in either direction from the gear 70 in order to turn 30 the disk 72 and move the tape 27 through positive engagement of the teeth 73 in the openings 74. Thus the shaft 71 may have a gear wheel thereon as at 75 above the supporting plate or wall 19.
- 35 To provide for reverse rotation of the shaft 71, a lever 45 has a plurality of gear wheels 76 and 77 journaled thereon as at 78 and 79. It will be seen that one of the gear wheels 76 or 77 is in engagement with 40 the gear wheels 70 and 75, and the other gear wheel is disengaged therefrom. Such engagement will drive the shaft 71 in one direction. When the lever 45 is shifted, the other gear wheel 76 or 77 will mesh with the gear wheels 70 and 75, thus driving the 45 shaft 71 in the opposite direction.
- A suitable escapement mechanism is associated with the parts described and to this end a shaft 80 is journaled as in bearings 81 within casing section 11. A gear wheel 82 is keyed on said shaft 80 and meshes with a gear wheel 83 keyed on said shaft 46. At 84, a ratchet wheel is keyed on shaft 80 with which a detent 85 cooperates. Detent 85 is journaled on shaft 46 and has a lug 86 adapted to engage the teeth of the ratchet wheel 84. Associated with the detent or arm 85 is a fastening link 87 pivoted at 88 within casing section 11. Detent 85 has a hook end 89 to engage over the detent 85 when in engagement with the ratchet 84. A spring 90 urges the arm 87 into position engaging the lug 86. Detent arm 85 rests on a cam 91 keyed to shaft 80 so that said cam will
- prevent too rapid return of arm 85 to normal position, thus controlling the period of escapement. A spring is provided at 92 to normally urge the arm 85 into engagement with the cam 91. Adjacent the cam 91, a gear wheel 93 is keyed to the shaft 80 which meshes with a gear wheel 94 keyed to shaft 46.
- Secured to the detent is a wire or cable 95 which is guided on the car in any suitable manner as by one or more pulleys 96 and which passes exteriorly of the car and is secured to a lever 97 pivoted at 98 on the trolley pole D. A spring 99 is connected to the pole and to the lever 97 to retain said lever in a normal position against a stop 100.
- Along the route traversed by the car A at each street or stop, a suitable abutment is provided to tilt the lever rearwardly 85 which thereby draws the cable 95, elevating detent 85 to release the escapement. From the wire E may be supported, one at each side street or intersection between a main street, an abutment plate 101, disposed 90 in the path of movement of the lever 97.
- A suitable switch for motor 55 is provided. This motor is shown in an electric circuit in Figure 13. The source of current utilized is shown at 102 having a conductor 103 leading to the motor and a conductor 104 leading to a contact 105. A conductor 106 leads from the motor to a contact 107. The circuit through the motor 55 will be closed upon engagement of contacts 105 and 107. 100 As to the switch proper, contact 107 may be stationary and arranged in suitable insulated relation on the top of section 11. Contact 105 is also disposed on and insulated from the top of the casing 11, being pivoted as at 108 to swing into engagement with contact 107. Contact 105 is normally urged into a disengaged position against a stop 109 by a contractile spring 110. The switch is adapted to be closed at suitable intervals 105 and to this end a gear wheel may be provided at 111, journaled on a bolt or stub shaft 112 to the top of section 11. Gear wheel 111 is driven by a gear wheel 113 meshing therewith and keyed to the shaft 49. An abutment 114, preferably of insulating material, is disposed on the gear wheel 111 so that as the gear wheel 111 turns, abutment 114 will strike the contact 105 and depress or swing it into contact with the contact 107. After the abutment 114 passes over contact 105, its spring 110 restores it to normal or open circuit position.
- In practice, the motor 50, through its shaft 54 and gearing drives the gear 69 and shaft 46 and gear wheel 70. The latter, through the medium of the selected gear 76 or 77 drives gear wheel 75 which drives shaft 71 causing the disk 72 to cause travel of the tape 27 in the appropriate direction. The 110
- 115 120 125 130

motor 34 at the same time expends its energy so as to wind the tape about one of the spools 12 to the same extent that it is unwound or unwrapped from the other 5 spool, thus maintaining it in a taut condition across the opening 30. The winding action of the spring 34 is of course limited to the amount of tape fed by disk 72 under control of their operating gearing and 10 motor 50. At the desired time, the tape is adapted to be moved in the manner stated but normally it is stationary. When it is desired to operate, cable 95 is drawn through engagement of lever 97 with the 15 abutment 101 thus elevating the detent 85 and releasing the escapement mechanism, permitting the parts to operate until the cam 91 moves from the position of Figure 12 to the position of Figure 11, where the 20 parts are again locked against movement by engagement of arm 86 with ratchet 84. As the parts operate, the contacts 105 and 107 are appropriately engaged at desired times to actuate motor 55 to rewind the 25 shafts 49 and 33 through the medium of the worm 53, worm wheel 52 and appropriate gearing, pawl 64 and ratchet 66. It is to be understood of course that the means for operating the detent shown is by way 30 of example only and that other means may be used or substituted therefor. For instance a means may be employed beneath the car as illustrated in Figures 15 and 16. In said figures, the equivalent of cable 95 35 is shown at 115 passing through a suitable tube 116, which may be rigid and secured to a part 117 of the truck of the car. A bell crank lever 118 is pivoted to the sleeve 116 as at 119 and cable 115 is connected to one 40 arm of said lever. A resilient or spring section 120 is provided in the cable 115 so that slight vibratory action of the lever 118 will not draw the cable sufficiently to release the detent 85. The other arm of lever 118 is 45 adapted to engage track obstacles 120 disposed at suitable locations along the roadway. With the engagement of levers 118 with the track obstacles, the levers are tilted which exert a drawing action on the cable 50 115 and accordingly elevate the detent 85.

Changes in the details and principles may be resorted to within the spirit and scope of the invention since merely one practical embodiment has been illustrated and described.

I claim as my invention:—

1. An exhibitor for a moving body having an exhibiting member, a spool therefor, a driving member for the spool, a detachable 60 connection between said spool and member consisting of a spring controlled stud movable longitudinally of the axis thereof and a pin and elongated slot connection between the spool and member for unitary rotation

thereof and permitting detachment of the 65 spool and member by movement in a plane transversely of the spool.

2. An exhibitor having an exhibitor member, an actuating mechanism to periodically move said member in the same direction, a 70 spring motor to expend its energy to drive said mechanism, and means operable through movement of said mechanism in the intervals between operations of the exhibitor member to rewind said spring motor without affecting the direction of movement of the exhibitor member. 75

3. An exhibitor having an exhibiting member, an actuating mechanism, a spring motor to periodically operate said mechanism to move said member in the same direction, and a motor operable in the intervals between operations of the exhibitor member to wind said spring motor to compensate for expended energy without affecting the direction of movement of the exhibitor member. 80

4. An exhibitor having an exhibiting member, an actuating mechanism, a spring motor to periodically operate said mechanism to move said member in the same direction, and a spring motor operable in the intervals between operations of the exhibitor member to wind said spring motor to compensate for expanded energy without affecting the direction of movement of the exhibitor member, and a control switch in the circuit of said electric motor operable through 90 actuation of said mechanism. 95

5. An exhibitor having an actuating mechanism, a spring to operate the same, a motor, means to wind said spring from said motor including a shaft, switch means in the circuit of said motor operable through the movement of said shaft including a rotary member, and a cam on said rotary member directly engageable with said switch. 100

6. An exhibitor having an actuating mechanism including a shaft, an operating spring to turn said shaft, an electric motor, a worm driven by said motor, a worm wheel on said shaft in mesh with said worm, a gear wheel on said shaft, a second gear wheel, said second gear wheel meshing with said first gear wheel, a cam on said second gear wheel, and a switch in the circuit of said electric motor operable by said cam. 110

7. An exhibitor, having an actuating mechanism, an escapement means for said mechanism, means to actuate said escapement means, and means additional to the escapement means to retard return of said escapement means into engagement with said mechanism. 120

8. An exhibitor having an operating mechanism, an escapement means therefor, means to disengage said escapement means 125

therefrom, and a cam in the path of return movement of the escapement means to retard its return to normal position.

9. An exhibitor having an actuating mechanism, a ratchet wheel cooperating therewith, a pivoted detent member normally engaging said ratchet wheel, a cam in engagement with said detent member, and means operable to disengage said detent member from said ratchet wheel and said cam serving to retard return of said escapement means into engagement with said mechanism.

10. An exhibitor having an exhibiting member, spools operable to wind and unwind said member, means operable to selectively establish communication between a source of driving power and said spools, consisting of a lever, a driven shaft on which 15 said lever is fulcrumed, a gear wheel on said shaft, gear wheels on said lever to selectively mesh with the first mentioned gear

wheel, feed means for the exhibiting member having a gear wheel, and the gear wheels of the lever adapted to selectively mesh with 25 the first and last mentioned gear wheels through movement of said lever.

11. An exhibitor having an exhibiting member, drive means for said member including a shaft, winding means for said 30 member including a shaft, means operable to turn one of said shafts, and a pawl and ratchet connection between said shafts whereby they may be turned simultaneously, motor springs connected to said shafts, and 35 said pawl and ratchet connection permitting one of said shafts to turn independently of the other.

In testimony whereof I affix my signature in presence of two witnesses.

DIRK A. KLEIMAN.
